UNITED STATES PATENT OFFICE.

RICHARD LEONARD MOYLE, OF NEW YORK, N. Y.

COMBINATION-TILES FOR FLOORS, WALLS, &c.

SPECIFICATION forming part of Letters Patent No. 724,394, dated March 31, 1903.

Application filed April 12, 1902. Serial No. 102,570. (No model.)

To all whom it may concern:

Be it known that I, RICHARD LEONARD MOYLE, a citizen of the United States, residing in New York city, State of New York, have invented a new and useful Improvement 5 in Combination-Tiles for Floors, Walls, &c., of which the following is a specification.

My present invention is an improvement on my prior invention, for which Letters Patent 10 of the United States No. 695,647 were granted.

The object of the present invention is to secure all the advantages obtained by a three-piece tile floor and yet to construct a tiled floor formed of two pieces, so that the expense 15 of manufacture may be lessened, two molds only being necessary instead of three.

The combination -tile floor of my present invention is especially adapted for the floors and walls of residences, though it may be 20 employed on any floor, wall, or on decks of boats, &c., and the peculiar configuration of the tile makes many beautiful color combinations possible.

The improvement I am about to describe 25 is such that no two tiles taken by themselves interlock. The combination of tiles is effected by using two tiles of different forms without either locking the other.

Figures 1 to 3 of the drawings illustrate the 30 invention.

Similar letters refer to similar parts.

Fig. 1 is a plan view showing two forms of integral pieces forming a combination-tile. Figs. 2 and 3 are perspective views of the two 35 different tiles used in Fig. 1.

Tiles A have certain recesses *a*, into which fit the projections *e* of tiles B. Tiles B have recesses *c*, into which fit the projections *d* of tiles A. It is thus seen that while separate 40 from the rest no tile A locks a tile B; yet by the arrangement shown in the drawings the

combination of tiles forms a rigid non-shifting floor.

In making this tile an elastic material preferably is used; but any other suitable material may be employed. 45

I claim as my invention—

1. A tile flooring constructed of tiles of two different forms A and B, substantially as described. 50

2. A combination-tile floor formed of tiles of two different forms, so arranged that no single couple of such tiles, separated from the rest, interlock, and constructed with recesses and projections in one form of tile corresponding with projections and recesses in the other form, substantially as described. 55

3. A tile flooring constructed of tiles of two different forms, adapted so that one tile B, catches four tiles A, and arranged so that no single couple of tiles separate from the rest interlock, substantially as described. 60

4. A tile flooring constructed of tiles of two different forms, each presenting a recess on one or more of its faces, having their faces forming angles of any suitable degrees, so arranged that no single couple of tiles separate from the rest interlock, substantially as described. 65

5. A tile flooring constructed of tiles of two different forms, one of which A is arrow-shaped so that its recesses will conform to the projections of the other tile, substantially as described. 70

In testimony whereof I have signed my name to this specification, in the presence of two subscribing witnesses, this 5th day of April, 1902.

RICHARD LEONARD MOYLE.
